Primary Examiner — Mark Goodwin(74) *Attorney, Agent, or Firm* — Finnegan, Henderson, Farabow, Garrett & Dunner, LLP(57) **CLAIM**

The ornamental design for a interior beltline of a truck, as shown and described.

DESCRIPTION

FIG. 1 is a front view of an interior dashboard and doors as seen from the center of a truck cab with the steering wheel removed and the doors fully open, the doors not being included in the claimed design;

FIG. 2 is a top front view of the interior dashboard from FIG. 1;

FIG. 3 is a top view of the interior dashboard from FIG. 1 as seen from above showing storage areas in a top of the dashboard; and,

FIG. 4 is a front view of an outward-facing surface of a center switch stack from FIG. 1 as seen from the driver's position. The broken lines shown in the figures illustrate portions of the interior beltline of a truck that form no part of the claimed design. The rear view of the interior beltline and dashboard are not visible during ordinary use and are not part of the claimed design.
